DESIGN FOR A FINGER RING

Linus F. Heberger, Rochester, N. Y., assignor to
Metal Arts Company, Rochester, N. Y.

Application March 6, 1939, Serial No. 83,368

Term of patent 3½ years

To all whom it may concern:

Be it known that I, Linus F. Heberger, a citizen of the United States, residing at Rochester, in the county of Monroe and State of New York, have invented a new, original, and ornamental Design for a Finger Ring, of which the following is a specification, reference being had to the accompanying drawing, forming a part thereof.

Figure 1 is an end elevation of one end of the finger ring showing my new design.

Figure 2 is an end elevation of the other end of the finger ring.

Figure 3 is a top plan view thereof.

Figure 4 is a front elevation thereof.

I claim:

The ornamental design for a finger ring, as shown.

LINUS F. HEBERGER.
